WHEEL

John A. Main, East Lansing, and Millard F. Harty, Jr.,
Bloomfield Hills, Mich., assignors to Motor Wheel
Corporation, Lansing, Mich.

Filed Apr. 23, 1970, Ser. No. 22,592

Term of patent 14 years

Int. Cl. D12—14

U.S. Cl. D14—30

FIG. 1 is a perspective view of a wheel as viewed from the outboard face showing our new design.

FIG. 2 is a front elevational view of the wheel of FIG. 1 and slightly enlarged thereover.

FIG. 3 is a sectional view taken on the line 3—3 of FIG. 2.

FIG. 4 is a sectional view taken on the line 4—4 of FIG. 2.

FIG. 5 is a fragmentary sectional view taken on the line 5—5 of FIG. 2.

We claim:

The ornamental design for a wheel, substantially as shown.
